(57) **CLAIM**

The ornamental design for front cover portion of a handset, as shown and described.

DESCRIPTION

FIG. 1 is a bottom view of a front cover portion of a handset showing my new design in isolation;

FIG. 2 is a right side view thereof;

FIG. 3 is a front view thereof;

FIG. 4 is a left side view thereof;

FIG. 5 is a top view thereof;

FIG. 6 is a perspective front view thereof;

FIG. 7 is a bottom view of the front cover portion of a handset showing my new design illustrating the front cover within an environment of a remainder of a handset.

FIG. 8 is a right side view thereof;

FIG. 9 is a front view thereof;

FIG. 10 is a left side view thereof;

FIG. 11 is a top view thereof; and,

FIG. 12 is a perspective front view thereof.

The broken line showing of the remainder of the handset in FIGS. 7-12 is for illustrative purposes only and forms no part of the claimed design.
